Primary Examiner — Leanne Was-Englehart*Assistant Examiner* — Yelizaveta Y Masalimova(74) *Attorney, Agent, or Firm* — Vladimir Postnikov(57) **CLAIM**

The ornamental design for a sandal, as shown and described.

DESCRIPTION

FIG. 1 is a top perspective view of a sandal showing my new design;

FIG. 2 is bottom perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the encircled portion 9 in FIG. 2; and,

FIG. 10 is an enlarged view of the encircled portion 10 in FIG. 2.

The dash-dot lines in FIGS. 2, 9 and 10 illustrate the boundaries of the enlarged view indicators and form no part of the claimed design.

1 Claim, 10 Drawing Sheets
